FOREIGN PATENT DOCUMENTS

0 258 826 3/1988 European Pat. Off. B62B 7/08

Primary Examiner—Kay H. Chin**Attorney, Agent, or Firm**—Robert G. Crouch; Holland & Hart LLP**[57] CLAIM**

The ornamental design for a stroller, as shown and described.

DESCRIPTION

FIG. 1 is a perspective view of the retro-look carriage stroller showing our new design;
 FIG. 2 is a front elevation thereof;
 FIG. 3 is a rear elevation view thereof;
 FIG. 4 is a left side elevation view thereof;
 FIG. 5 is a top plan view thereof;
 FIG. 6 is a bottom plan view thereof;
 FIG. 7 is a right side elevation view thereof; and
 FIG. 8 is a perspective view of the retro-look carriage stroller with the canopy retracted.
